ALLEN E. OSTRANDER, OF RIDGEWOOD, NEW JERSEY.

DRAFT-GEAR ATTACHMENT OR COUPLING-YOKE.

1,122,412.

Specification of Letters Patent. Patented Dec. 29, 1914.

Application filed July 22, 1912. Serial No. 710,856.

To all whom it may concern:

Be it known that I, ALLEN E. OSTRANDER, residing at Ridgewood, New Jersey, and being a citizen of the United States, have invented certain new and useful Improvements in Draft-Gear Attachments or Coupler-Yokes, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

My invention relates to a draft gear attachment or coupler yoke and mountings for the same in a car construction.

An object of the invention is to provide a unitary draft gear attachment adapted to certain a conventional form of draft gear, which attachment may be readily and conveniently mounted and dismounted as a unit to and from its position between the draft sills without affecting the coupler, and also arranged so that the coupler may be removed without disturbing the draft gear yoke itself. Ancillary to this desideratum it is an object to provide an uninterrupted zone of travel between the draft sills for the coupler yoke.

A further object is to provide a device of the above indicated character so constructed that members thereof subjected to tension strains are made of rolled steel having high tensile strength while the other parts may be castings, all arranged, devised and united to form a simple, easily constructed and reinforced device; and a still further object of the invention is to minimize the number of necessary parts by utilizing one element for several functions.

Figure 1 is a plan view looking down upon an illustration of a preferred physical embodiment of my invention. Fig. 2 is a vertical sectional view taken in a plane passing through the longitudinal center of Fig. 1 on the line 2—2 of this figure. Fig. 3 is a vertical transverse sectional view taken on a plane indicated by the line 3—3 of Fig. 2, looking in the direction indicated by the arrow. Fig. 4 is a similar view taken

on the line 4—4 of Fig. 2, also looking in the direction indicated by the arrow. Fig. 5 is a view similar to Fig. 4 taken on the line 5—5 of Fig. 1, looking in the direction of the arrow. Fig. 6 is a plan view of the rear end of a draft yoke forming a modification of the form shown in Figs. 1 and 2. Fig. 7 is a side elevational view of the parts shown in Fig. 6. Fig. 8 is a rear elevational view of Figs. 6 and 7. Figs. 9, 10 and 11 are views similar to Figs. 6, 7 and 8 of another modified form of draft yoke end. Figs. 12 and 13 are respectively front side elevation and top plan views of the front stop, shown in dotted lines attached to the outside of the sills in Figs. 1 and 2. Fig. 14 is a transverse sectional view taken on the line 13—13 of Fig. 12, looking in the direction indicated by the arrow. Figs. 15, 16 and 17 are respectively side elevation, plan and front end elevational views of the front follower detached from its co-operating parts. Fig. 18 is a side elevation of one of the yoke struts. Fig. 19 is a front elevational view of the same, and Fig. 20 is a side elevation of the forward end of one of the yoke straps or loops.

In the several views I have shown a vehicle for my improved invention, including conventional parts and, for the purpose of illustration, I have shown a pair of transversely spaced apart draft sills A in the form of outwardly facing channel bars spaced apart a regulation distance, the outer ends of which sills are fastened together by the usual end sills and co-acting parts B. Spaced to the rear of said end sills and extending transversely across the draft sills is the usual top bolster plate C, beneath which bolster plate and connecting the sills A is the bolster center filling casting D fastened by means of the rivets d to the inner face or web of each of the sills A, the said casting having extending inwardly from its forward ends transversely spaced vertically disposed ribs or stops d', taking the place of the follower stops usually affixed to the inner faces of the draft sills.

It will be noted from this construction that there is a clear, unobstructed passage between the rear follower stops d' and the end sill B, within which space may be disposed my improved draft gear attachment occupying the entire transverse space be-

tween sills, which arrangement tends to facilitate the mounting and dismounting of the draft gear yoke.

Fastened by means of rivets e^2 to the underside of the lower flange of the sills A and bridging the space between the same and positioned in advance of the rear stops d' a distance equal to the normal forward travel of the draft yoke is a guide bracket E, affording means in addition to the casting D for maintaining the sills in spaced relation, and having a top recess e affording a means for supporting the draft gear and having tracks e' on opposite sides of the recess e for supporting the loops, hereinafter described, at the required height of the sill from the rails.

Positioned between the sills A and filling the space transversely between the same is the draft yoke G, particularly forming the subject-matter of this invention, which draft yoke comprises a pair of transversely spaced yoke loops 21, each yoke loop being in the form of a horizontally disposed U strap or rolled bar slidably mounted on a track e' adjacent its contiguous draft sill A. Each of these loops are similar in configuration, so that a detailed description of one will suffice for both.

Each of the yoke loops 21 comprise parallelly extending horizontal legs 22, the forward ends of which are formed into slightly converging portions 23, which portions are continuous around the bend or crotch 24. Adapted to extend transversely through the sills A, loops 21 and coupler shank F is a flat horizontally disposed pin or key 25, affording means for supporting the coupler shank from the draft sills A, the pin 25 being positioned in a horizontally disposed elongated slot 26 in the draft sills, said slots being of a length equal to at least twice the normal travel of the coupler shaft F plus the width of the key 25, whereby said key 45 may travel in either direction from its normal central position with the coupler.

In order to brace the flange of the draft sills at these slots, the same are outlined by a slotted stop casting 27 (see Figs. 12 and 50 13), which casting is suitably fastened by means of the rivets 28 to the outside of the web of the draft sills A. It will be understood that the slot 26' in the casting coincides with and, as shown in Fig. 3, outlines 55 the slot 26 in the draft sills.

It will be seen from the illustrations that a forward pull on the coupler shaft F acting through the pin 25 will draw the draft yoke, including the loops 21, forward, which movement will cause the pin 25 to engage the crotch 24, giving rise to a tendency to draw the legs 22 and the converging portion 23 toward each other, which would have the effect of binding or preventing the free forward movement of the yoke member hereinin-

after described. To prevent this there is inserted between the legs 22 or inclined portion 23 of each of the yoke loops a strut 29. (See Figs. 18, 19 and 20.) This strut has a material body portion 30 rectangular in cross section and having shoulder forming ends conforming to the configuration of the contacting surface of the adjacent loop, and extending from each of which ends are studs 31, in this case shown to be angularly disposed, 75 and adapted to engage apertures 32 extending through or recessed in the inner face of each of the portions 23. Extending rearwardly from the upper and lower ends of the rear face of said strut, and preferably 80 integral with the same, are top and bottom brackets 29' adapted to overlap and effectively brace the yoke loops at the point or angle where portions 23 begin to converge.

Disposed between the draft sills and between the legs of the yoke loop 21 and slidably mounted therein is the head 33 of a T-shaped front follower casting 34, the rear face of which head is defined by a recessed portion or ring 35, affording a pocket to 85 contain one end of the spring sets, friction elements or other mechanism constituting the draft gear, these mechanisms forming no particular part of this invention.

The opposite or front end of the follower 95 34 has a pair of transversely disposed vertically extending ribs or lugs 36, between which is positioned the rear end of the coupler shank F, so as to prevent transverse movement of this member. In order to 100 lighten the follower it is cast hollow or cored, as shown in Figs. 1 and 3, and in order to brace the head to the stem or body portion a triangular shaped horizontally disposed bracket 37 is cast in each of the 105 angles between the head and stem. The stem of this front follower has a horizontally disposed kerf or slot 48 extending rearwardly from the front face thereof (see Figs. 2 and 15) for a purpose hereinafter 110 disclosed.

Extending parallel to the key 25 and passing horizontally through the front follower 34, draft sills A and between the legs of the yoke loop 21, is a flat horizontally disposed locking key 38 slidably disposed in the slot 48, said key riding in a slot in each of the draft sills, which slots coincide with a bearing slot 39, which, as shown, may be contained in the casting 27, or may be a casting 120 or plate independent of plate 27. Both the slots 26' and 39 may be outlined by a rib 40, shown more particularly in Fig. 14, so as to afford a relatively wide bearing or riding surface for the keys 25 and 38.

Referring to Fig. 2 it will be noted that the members are in their normal position in which the key 25 is in position substantially centered in the slot 26', the play on this key in either direction being equal to the maxi- 130

5. minimum allowable travel of the coupler shaft; that is, in general practice about $3\frac{1}{2}$ '. In order to prevent any possibility of a ripping of the key from its bearings, this slot 25' may be made slightly longer toward the rear of the key when in normal position, so that a buffing action will be taken up entirely on the ribs d' rather than the pin 25.

10. Constituting the rear of the yoke and bridging the space between the yoke loops 21 is a rear follower casting 41, several modifications of which are disclosed in the drawings. In general, the forward face of the rear follower casting includes a recess 15 42, similar in outline, facing and in alignment with the recess 35 and constituting a rear pocket to receive the draft gear.

20. As shown in the modifications disclosed in Figs. 1 and 2, the free ends of each of the legs 22 are turned inward toward each other and inserted into vertical side recesses 43 at the top and bottom and on each side of the casting 41, the ends being held in position within the follower by means of the horizontally extending rivets 44.

25. As shown in the modification disclosed in Figs. 6, 7 and 8, the free ends of the legs 22 are turned toward each other, and each end is upset to form a broad portion 45, which broad portions 45 are inserted by a transverse movement in a vertically extending slot 46 on each side of the rear follower casting 41. By this construction it will be noted that the ends of each loop are held in position by the adjacent draft sill A, thus affording a convenient means for holding these members in assembled position.

30. As shown in the modification disclosed in Figs. 9, 10 and 11, the free ends of the legs 22 are bent toward each other and fitted within a shouldered pocket 47 formed at the top and bottom of the transverse sides of the rear face of the casting 41, in this instance the members being held in position 35 by means of vertically disposed rivets 48 passing through the legs 22 and body of the casting 41.

35. Referring particularly to Figs. 1 and 2, it will be seen that a forward pull on the coupler shank F will act through the pin 25, loops 21 and rear follower 41 to draw the latter forward on the bracket or seat E, compressing the draft gear disposed between the pockets formed by the recesses 35 and 42, and causing the loops 21 to draw away from the front follower casting 34, the key 38 holding the front follower casting 34 in the position shown in Fig. 2, with the key engaging the front end of the slot 39, thereby transferring the strains to the draft sills A. The pull on the coupler shank being released the draft gear will cause all of the members to assume the position shown in Figs. 1 and 2.

40. A buffing action on the coupler shank F

will act directly on the front follower 34, causing the same to move rearwardly on the pin 38, compressing the draft gear, and a further movement of the coupler shank in buffering will carry the front follower 34 and 45 the pin 38 rearwardly until the pin contacts with the rear end 49 of the slot 39, at which point the draft gear will be compressed to its full capacity, transmitting the strains to the rear follower 41 and through the same 50 to the draft stops d' , or to the draft sills A through the bolster filler plate D.

55. An important advantage of this construction is that the coupler yoke may be removed as an entity from its position between the draft sills without affecting the position of the coupler shaft. It will be understood that by withdrawing the cotter pins 50 from the keys 25 and 38 these keys may be withdrawn transversely from either 60 side of the draft gears and the forward end of the coupler yoke allowed to drop and then slide forward until the rear end has cleared the bracket E. The draft members 65 may be reinserted by a reversal of this 70 movement.

75. A further advantage of this construction is that the coupler shank may be removed without disturbing the arrangement of the coupler yoke, this being attained by withdrawing the pin 25 transversely through the 80 sills and drawing the coupler shank F forwardly through the end sills.

85. In order to form an economical construction that will withstand the strains incident to a device of this character, the yoke loops 21 are made of a high grade rolled steel, as it is these members that must withstand the heavy tension strains, while the front and rear followers may be made of a 90 cheaper form of material and are preferably castings; as the castings may be readily molded into the desired shape and are not subjected to severe tension strains.

95. While the unobstructed passage between 100 end sill and rear follower stops is shown, it is to be understood that this unobstructed passage need not extend to the end sill, but should extend within the entire zone of movement of the yoke either in service or in 105 110 movement of mounting and removal.

115. Having thus described my invention what I claim as new and desire to protect by Letters Patent of the United States is

120. 1. A draft gear attachment comprising a pair of spaced open yoke loops and a casting constituting the rear follower positioned within the outlines of said loops and connecting the same, and connecting parts of each loop.

125. 2. In combination, a draft yoke comprising a pair of spaced open loops, a rear follower uniting the ends of each of said loops and connecting the pair of spaced loops.

130. 3. In combination a draft yoke comprising

ing a pair of spaced open loops, a rear follower uniting said loops and the ends of each of said loops, a front follower movably mounted within said loops and a supported bracket carrying one end of said draft yoke.

4. In a car, slotted spaced draft sills with unobstructed opposing faces, a pair of spaced open yoke loops and a casting 10 constituting the rear follower positioned within the outlines of said loops and connecting the same and connecting parts of each loop, a bracket bracing said draft sills in position and having parallel tracks supporting one end of said yoke and a movable 15 key supporting the other end of said yoke.

5. In a draft gear attachment a yoke formed with spaced-open loops, a rear connecting member inclosing the ends of said 20 loops and constituting a rear follower, and a front follower slidably mounted between said loops.

6. The combination of draft sills, a follower occupying substantially the trans- 25 verse distance between the sills, said follower having a recess therein adjacent a contiguous sill, and a coupler loop having a portion positioned within said recess and held from transverse movement by said sill.

30 7. The combination of draft sills, a follower occupying substantially the transverse distance between the sills, said follower having a recess therein adjacent a contiguous sill, a coupler loop having a portion positioned within said recess and held from transverse movement by said contiguous draft sill, said loop having an upset end within said recess holding the loop from vertical movement.

40 8. The combination of draft sills, a follower occupying substantially the transverse

distance between the sills, said follower having a recess therein, a coupler loop having an end positioned within said recess, said end being upset to prevent the withdrawal 45 of same from the recess.

9. In a draft gear yoke, a U-shaped rolled-metal loop, a rear follower positioned between and uniting the free ends thereof, and a removable bracing strut between the legs thereof to maintain the same in spaced relation.

10. The combination of draft sills, a draft yoke comprising a rear follower, a pair of vertically disposed spaced open loops extending forwardly in fixed relation from said follower, said follower being positioned within the outlines of said loops and connecting the same, a front follower disposed within both of said loops, a key supporting said front follower from said draft sills, and a member depending from said sills having a portion supporting said loops.

11. In a draft gear yoke, the combination 65 of spaced U-shaped loops, each having a converging crotch end, a spacing member within said crotch end, and a rear follower for a draft gear connecting their opposite free ends.

12. In a draft gear yoke, the combination of spaced loops converging at one end, a spacing member within said end and a rear follower for a draft gear lapping their opposite ends and being positively connected 75 therewith.

In witness whereof I have hereunto set my hand in the presence of two witnesses.

ALLEN E. OSTRANDER.
